PREHEATER APPARATUS FOR OIL BURNERS

Filed Dec. 10, 1928

INVENTOR,
A. J. BAIRD.
BY Horace Barnes
ATTORNEY.

UNITED STATES PATENT OFFICE

ARTHUR J. BAIRD, OF PORTLAND, OREGON

PREHEATER APPARATUS FOR OIL BURNERS

Application filed December 10, 1928. Serial No. 324,902.

This invention relates to improvements in apparatus for preheating fuel oil for maintaining combustion in oil-burning furnaces, and particularly of the type of apparatus described and claimed in my prior patent application Serial No. 229,149, filed October 27, 1927.

The principal object of my invention is to provide simple and self-regulatory apparatus for heating fuel oil preparatory to its injection into a furnace and to maintain the temperature of the oil above a predetermined minimum whereat the oil atomization is productive of most efficient results in combustion.

A further object of the invention is the provision in preheating apparatus for oil burners of steam-heating and electric heating elements in operative conjunction and whereby the electric heating devices may be utilized prior to the raising of sufficient steam for heating purposes or when the steam heat fails for any reason, said auxiliary electric heating devices being constantly available automatically under effective thermostatic controls.

A still further object of my invention is the provision in a preheater for oil burners of a venting device communicatively connecting the heating chamber wherein the oil is warmed for delivery to the burner and the passage for the cold oil into such chamber whereby gases generated in the heating chamber may be withdrawn from the chamber to be mingled with and absorbed by the incoming oil and thus avoiding the danger of accumulation of gases in the chamber.

Other objects and advantages residing in my invention and objects relating to details of construction and relative arrangements of parts thereof will be readily apparent in the course of the detailed description to follow.

The accompanying drawings illustrate by way of example a preferred form of my invention, in which:

Figure 1 is a view substantially in medial vertical section of an embodiment of my invention with accessory parts thereof shown in side elevation.

Fig. 2 is a top plan view of the main body

of my improved preheater as on line 2—2 of Fig. 1.

Fig. 3 is a view in side elevation of the invention with the thermal control apparatus removed, and with the lower portion of the 55 preheater shown in section.

Fig. 4 is a view in horizontal section on line 4—4 of Fig. 1.

Referring to said views, the reference numeral 1 indicates a casing having a substantially cylindrical heating chamber 2 which is closed at its bottom by a plate 3.

At the upper end the casing is formed with a laterally directed L-extension 5 having a discharge chamber 6 therein open to its full extent from the heating chamber. A discharge-pipe 7 for the heater oil extends through the bottom wall of the extension to near the top thereof where its opening 8 for the ingress of the oil is in close proximity to the top of the chamber 6 so that only the warmest oil in the heating and discharge chambers will be withdrawn. The discharge pipe is communicatively connected to a burner of any type.

Upon the opposite side of the casing a pipe 10 leads from a source of oil supply under pressure and is communicatively connected with a vertically disposed passage 11 formed in the casing wall. The pressure upon said oil supply may be applied by means of a gravitational system or through a pump, not shown. The oil issuing through the passage 11 takes a vertically upward course and passes through a cell 12 formed in the casing whence 85 the oil flows downwardly through a passage 13 and inlet port 15 into the heating chamber adjacent its bottom.

A steam-coil 16 is connected at one end centrally of said bottom plate with a pipe 17 through which the condensations are carried to a steam-trap 18. The opposite end of said coil extends through the upper wall of the casing where it is connected to a feed-pipe 19 extending from a boiler for generating steam, not shown, to which the apparatus pertains.

The numeral 20 indicates an electric heating element of the immersion type extending, preferably, through the upper wall of 100

the casing and into the chamber 2 centrally of the steam-coil spirals.

At the upper end of the heating chamber 2 a tube 21 extends through the interior wall 5 22 separating the chamber from the cell 12 and communicatively connects said chamber and cell through its bore 23. The tube is of relatively small bore and extends to within close proximity of the opposite side wall of 10 the cell and beyond the upper end of the passage 11 so that oil flowing through the passages and cell cannot readily pass by way of the tube into the heating chamber. A screw-plug 25 is screwed into the casing-wall 15 opposite the tube 21 through which the tube may be cleaned if it should become clogged for any reason. Said plug may be formed with a recess 26 on its inner side into which the tube may extend.

20 A thermally controlled switch housed in the box 27 is rigidly mounted on the casing through having its thermostatic element 28 extended horizontally into the discharge chamber 6 along the lower portion thereof and spaced 25 below the opening 8 of the discharge pipe. Said switch is adapted to make and break a circuit formed by wires 30 and including the heating element 20 whereby current is supplied to the element as a heating agency 30 for the oil in the heating chamber during such times as the temperature of the oil therein remains below a predetermined degree of heat for which the switch is set to break the circuit and as actuated by the thermostat 28.

35 Such temperature at which the switch is operated to break the circuit is desirably set at a degree of heat somewhat less than the heat of the steam supplied to the coil 16 or at about 140 degrees Fahrenheit at which temperature the oil is found to atomize at high 40 efficiency.

A thermometer 31 may be likewise mounted upon the casing and extended therethrough in a heat-responsive element 32 into 45 the discharge chamber 6.

The operation of my improved preheating apparatus may be briefly described as follows: With the apparatus assembled in operative condition as described and illustrated 50 and assuming that the fire is extinguished in the furnace, as in the case of starting the heating plant at the beginning of a day, the current is turned through the wires 30 as by a manually operated switch, not shown, 55 which will energize the heating element to heat the oil in the chamber 2 with which it is in contact. When the oil is warmed it rises and fills the discharge chamber at the top of the casing and when sufficiently warmed as 60 determined by the thermometer 31 the oil pump, not shown, or other feed or atomizing agencies required to inject the oil into the furnace are actuated whereupon the oil is forced through the pipe 7 to the oil-burner 65 under pressure while an equal amount en-

ters through the supply pipe and circulated through the passages 11 and 13 and heated in the chamber 2 where it flows upwardly while being subjected to the heat of the electric element.

As soon as steam is raised sufficiently in the boiler to enter the coil 16 the heat therefrom joins with the electrically generated heat to warm the oil until the latter reaches the predetermined temperature at which the switch controlled by the thermostat 28 is set to break the electric circuit whereupon the steam-coil is relied upon to furnish the entire amount of heat utilized unless the steam-heat in the coil should be insufficient at any time to maintain the oil circulating through the preheater at or above the prearranged minimum temperature at which the switch is set to close the circuit and again energize the heating element. Such utilization of the electric heating element as an auxiliary heating agency to the steam-coil as well as a preheater may take place frequently during the daily operation of the furnace and in practice it is found that the thermally controlled switch may be relied upon during the hours when the furnace is not in operation to maintain the oil in warm condition during such idle periods and in readiness for operation at any time and with a very small additional consumption of electric current.

It is found that the vapors arising from the heated oil will sometimes accumulate in the heating chamber and force the oil back into the supply pipe until the heating chamber is more or less emptied of oil. This will happen principally when the electric heating element is turned on and the burner is not in use, resulting in a serious obstacle to a proper circulation of the oil in the chamber. To guard against such collection of gases I have provided the tube 21 forming a communication between the upper end of the heating chamber 2 and the cell 12 so that any gases formed in the chamber will be carried into the cell to be absorbed by the incoming cold oil or in case the flow of oil is stopped as by closing down the furnace the gases will escape through the supply pipe without danger of emptying the heating chamber.

The provision of the discharge chamber as an annex to the heating chamber and the location of the discharge pipe opening relative to the thermostatic element through whose action the automatic switch is regulated whereby the oil at the top of the chamber and which is drawn off at its highest temperature while the thermostat is situated at a lower elevation and is surrounded by a strata of cooler oil thus promoting efficiency in ensuring that the oil issuing from the apparatus is always warmed to a suitable degree and that the action of the thermostat is moderated and the actuation of the switch

only takes place when there is considerable reserve supply of properly heated oil.

While I have described my invention for convenience and brevity as operative with steam-heating appliances it will be apparent that the apparatus is equally effective when utilizing hot water as a source for warming the oil in the chamber 2 and which requires only the provision of the usual pipe con-

10 nections to the boiler in addition to the appliances shown in place of the steam-trap 18 to establish a return circulation in a well understood manner and which is deemed the full equivalent with the employment of steam 15 and is so intended to apply both in the description and the claims relating to my improvement.

Having described my invention, what I claim is:

20 1. A preheater for fuel-oil, comprising a casing having a heating chamber communicatively connected with a source of oil supply under pressure and a discharge chamber in said casing communicating with the upper 25 end of said heating chamber, a steam-coil in said heating chamber, an electric circuit including a heating element extending into said heating chamber, a discharge pipe arranged to withdraw oil from near the top of said 30 discharge chamber, and a thermostatically controlled switch having a thermostatic element extending into said discharge chamber at an elevation below the opening into said discharge pipe and adapted to make or break 35 said circuit in response to changes in temperature of the oil.

2. A preheater for fuel-oil, comprising a casing having a heating chamber and a discharge chamber opening out of the upper end 40 of the heating chamber, an inverted U-shaped supply passage for oil having a ported opening into the heating chamber at the lower end thereof, a vent tube between the upper end of the heating chamber and said passage to admit of the escape of gases from the heating chamber, a steam-coil extending into said heating chamber, an electric circuit including a heating element extending into said heating chamber, and an electric circuit breaker 45 included in said circuit thermally controlled by a thermostatic element extending into said discharge chamber.

3. A preheater for fuel-oil, including the apparatus described in claim 2, together with 55 a discharge pipe in the discharge chamber having its withdrawal opening disposed at a higher elevation than the thermostatic element of the circuit breaker.

4. A preheater for fuel-oil, consisting in a 60 casing having a heating chamber therein, a steam-coil and an auxiliary electric heating element extending into said chamber to heat the oil therein, said heating element being included in an electric circuit, a circuit breaker in said circuit, a thermostatic element extend-

ing into said chamber adapted to actuate said circuit breaker upon predetermined changes of temperature of the oil, a supply passage for oil into said chamber opening into the lower portion of the chamber, a vent tube connecting the upper portion of said chamber and said supply passage, and a discharge pipe opening from the upper end of said chamber.
